J. N. McIntire

UNITED STATES PATENT OFFICE.

JACOB N. MCINTIRE, OF NEW YORK, N. Y., ASSIGNOR TO THE BRUNSWICK-BALKE-COLLENDER COMPANY, OF CHICAGO, ILLINOIS.

CUE-TRIMMER.

SPECIFICATION forming part of Letters Patent No. 546,121, dated September 10, 1895.

Application filed June 11, 1895. Serial No. 552,401. (No model.)

To all whom it may concern:

Be it known that I, JACOB N. MCINTIRE, a citizen of the United States, residing at New York, in the county of New York and State of New York, have invented certain new and useful Improvements in Cue-Trimmers, of which the following is a full, clear, and exact description, reference being had to the accompanying drawings, forming part of this specification.

My invention relates to "cue-cutters," or what are, more properly speaking, "cue-trimmers," and is an improvement on that species of device for trimming the end of a billiard-cue previous to retipping it in which a stationary knife is used, against which the end of the stick to be trimmed or shaved off is abutted and by which the wood is sheared off by turning the cue relatively to the knife while pressed up against it. This species of cue-trimmer has been made heretofore sometimes with a cutter the shearing-edge of which extended radially from the center to the circumference of the bore of the tubular stick-holder of the device and sometimes with a knife-edge extending diametrically across the entire bore; but in the latter construction the knife has been set always with its edge in a line slightly oblique to a plane or line transverse to the axis of the bore of the stick-holder, and in practice it has been found difficult, if not impossible, to either trim off the cue end square—*i. e.*, in a plane transverse to the axis of the tapering cue—or avoid cutting away too much of the stick at each trimming operation.

Another defect in or objection to the cue-cutters having the knife-edge arranged across the bore of the holder and in an oblique line, as they have heretofore been made, is that the usual knife-holding plate or disk, though usually centrally perforated, obstructs a free and immediate discharge from the device of the chips cut, so that the operator cannot see exactly how the end of the cue is being cut, and as the oblique knife cuts the stick with a helical shaving the cut is often made too deep before the operator discovers just how the tool is working.

I propose by my improvement to provide for use a cue-trimmer of the species alluded

to which shall be free of the defects above mentioned, that will be exceedingly efficient and desirable in operation, and that will be simple and economic of manufacture, while at the same time strong and durable.

To these main ends and objects my invention consists, essentially, in a cue-trimmer composed of a tubular handle-like holder and a knife or cutting blade fastened to one end thereof and arranged with its edge diametrically of and in a line transverse to the axis of the bore of said holder, the said bore and its transverse cutter being all exposed to view in a manner and for the purposes which will be herein presently fully explained, and as will be most particularly pointed out in the claim of this specification.

To enable those skilled in the art to which my invention relates to make and use cue-trimmers embodying the same, I will now proceed to more fully describe my improved construction, referring by letters to the accompanying drawings, which form part of this specification, and in which I have shown my invention carried into effect in that precise form of tool or device which I have so far made and used.

In the drawings, Figure 1 is an end or top view of a cue-trimmer made according to my invention. Fig. 2 is a longitudinal section at the line *xx* of Fig. 1. Fig. 3 is a perspective view of the holder or hand-piece with a portion broken away. Fig. 4 is a longitudinal section at line *yy* of Fig. 1.

In the several figures the same part will be found always designated by the same letter of reference.

The handle-like tubular holder *b* is made, preferably, of wood of any desired pattern or design which may be comfortably grasped by the hand of the operator, and with a central cylindrical (or slightly tapering) bore *b*², and in practice I have found it desirable to make this part about the size I have shown in the drawings, though both the size and shape of this holder part may be varied more or less, if deemed expedient. The bore *b*² should, however, be made of such size that it will accommodate within it, loosely, as shown by dotted line at Fig. 2, a cue of the largest diameter.

At Fig. 1 I have shown by a dotted circle the end of a cue of about the smallest diameter at the tip end, for the purpose of illustrating an operation to be hereinafter explained.

a is a knife or metallic cutter which is made, as shown, of about semicircular contour in plan or top view, (see Fig. 1,) but the blade portion of which is both bent and tapered downwardly, as best shown at Fig. 2. This cutter or knife *a* is securely fastened down to the top surface of the slightly-raised portion *f* of the end of the holder *b* by means of two wood-screws *c c*, and it is arranged, it will be observed, so that when fastened in its working position its cutting-edge will cross the upper end of the bore *b²* diametrically and in a line transverse to the axis of said bore.

The edge of knife *a* should rest, by preference, in contact with that part of the end of holder *b* which it overlies, and by having the projecting part *f* of the holder made full low a perfect and forcible contact of the edge of the knife with the end of handle *b* will be always assured in assembling the parts in the process of manufacture of the article or in replacing the cutter *a* whenever it may have been taken off for resharpening. I have sometimes made the edge of the knife *a* 30 slightly concave, instead of straight, with good effect.

I have found the degrees of taper shown of the upper and lower bent portion of the knife *a* to work well, though more or less variation thereof may be made, and, of course, were the under surface of this bent portion of the cutter made with more or less obliquity to the top surface of the holder *b* the part *f* of the latter would have to be made to project correspondingly more or less, compared with what is shown in the drawings.

It will be observed that if made of wood the handle *b* can be cheaply manufactured, as it needs only to be turned up approximately to a given exterior size and pattern, with a bore *b²* extending through it, and to then have the greater portion of its squared-off upper end sawed cross-cut and then slightly cut in the direction of the length at the vicinity of shoulder *e* to form the projecting cutter-seat *f*.

In using the device or tool shown the handle *b* may be grasped in the left hand and the cue inserted, as indicated by dotted lines at Fig. 2, whereupon, with the butt of the cue preferably resting on the floor, the operator, by grasping the body of the stick in his right hand and simultaneously turning it in the direction indicated by the arrow at Fig. 1, presses the knife-edge forcibly into contact with the cue end, and the latter will be evenly sheared or shaved off by the knife.

In operating the tool, as I have just explained, the device is held (in the left hand) with its cutter *a* nearest the body of the person using the tool, and in turning the cue, as explained, it is best to keep the latter pressed

laterally toward that side of the bore *b²* nearest to the body of the operator, especially if the cue be of full diameter, as otherwise in the cutting or dressing operation a slight seat may be left initially at the center of the cue end.

The dotted circle at Fig. 1, which represents the end of a small-sized cue, illustrates the correct or best position of the cue end while turned (substantially on its own axis) to effectuate the cutting. Of course these conditions may be somewhat reversed by the operator holding the cue still and turning (in an opposite direction) the holder *b*.

As both the cutting-edge of the knife and the cue end are exposed to view, the operator can easily see how the knife works, and as there is not the slightest impediment to the free escape of the chips by keeping them blown off while working the user of the tool can do the work with great nicety, manipulating the cue and cutter conjointly, so as to shave or trim off the least amount of stock necessary to properly dress the end of the stick for the reception of its new tip or "leather." This is of considerable importance, for, as every room-keeper knows, successive trimmings of the cues, which have often to be re-leathered, often shortens the cues so materially in a little while as to spoil or change their "balance," to the dissatisfaction of the players or users of the cues.

Unless the stock of the cue at the vicinity of its end shall have become slightly split down or slivered, (which does not often occur,) the least possible amount of the wood should be trimmed off for the retipping operation, and in practice, with my improved tool or device, this desired end is easily accomplished.

The cutter *a* is securely held in place (under a cheap construction) by the screws *c c*, while at the same time there is permitted an imperceptible degree of spring or yield to the cutting-edge that facilitates its perfect operation.

What I claim as new, and desire to secure by Letters Patent, is—

A cue-trimmer composed wholly of the tubular holder *b* formed with a projection *e*, wholly to one side of the bore; a cutter *a*, formed with a bent and tapered portion, having its edge transverse, or at right angles, to the axis of the bore *b²*, and crossing the end of said bore diametrically and with a body portion resting on the projection *e*; and the securing bolts, or screws *c*, operating to fasten the knife directly to the tubular holder; the whole constructed and operating in the manner and for the purpose hereinbefore set forth.

In witness whereof I have hereunto set my hand this 8th day of June, 1895.

J. N. MCINTIRE.

In presence of—

B. R. RYAN,
N. A. QUEENAN.
